[57] ABSTRACT

A pneumatically inflatable bag is positioned on a work supporting plate for advancing a work piece against a grinding wheel. The bag is backed by a plate on the work supporting plate which prevents the bag from movement away from the grinding wheel.

APPARATUS FOR FEEDING WORK TO A GRINDER WHEEL

This invention relates to an apparatus for feeding work to a grinder wheel by pneumatic pressure applied to an inflatable bag which urges the work against the wheel.

In foundries molten metal is poured in a sand mold to form a casting. In forming the casting there are metal risers on the casting which must be removed. This is done either by sawing the unwanted metal or grinding it from the casting, or a combination of both. The operation is known as cleaning the casting. The grinding is done by manually advancing the casting into the grinder wheel. It is known that operating in this fashion an operator is only able to remove about 25 pounds of metal per hour and with a result of great operator fatigue.

I have invented an apparatus for feeding work to a grinder in which 125 pounds of metal per hour can be removed, thereby reducing the time for grinding risers from the casting to one fifth of the time required by feeding the casting to the grinder manually. An operator is still used but the improved apparatus for feeding the work to the work to the grinder wheel greatly enhances the removal and the operator acts primarily as an operator of the feeding apparatus.

I provide an apparatus for feeding work to a grinder wheel which comprises a work supporting plate positioned adjacent to the grinder wheel and perpendicular to a grinding surface of the wheel, a pneumatically inflatable bag positioned on the work supporting plate and spaced from an edge of the work supporting plate nearest the grinder wheel to allow a work piece to rest between the grinder wheel surface and the inflatable bag, means supplying air to inflate the bag, and means preventing the bag from moving away from the grinder wheel when the bag urges the work to the grinder wheel.

Other objects, features and advantages of this invention will be apparent from the following description of a present preferred embodiment and a present preferred method of practicing the same.

In the accompanying drawings I have shown a present preferred embodiment of the invention and have illustrated a present preferred method of practicing it in which:

FIG. 1 is an isometric view of the apparatus;

FIG. 2 is a top view of the apparatus;

FIG. 3 is a rear elevational view of the apparatus shown in FIG. 2; and

FIG. 4 is a side elevational view of the apparatus shown in FIG. 3.

The apparatus comprises a work supporting plate 2 positioned adjacent to a grinder wheel 4 and perpendicular to a grinding surface 6 of the wheel 4. A pneumatically inflatable bag 8 preferably of elastomer material such as rubber is positioned on the work supporting plate 2 and is spaced from an edge 10 of the work supporting plate 2 nearest the grinder wheel 4 to allow the casting 30 with the riser to be inserted between the grinding surface 6 and the bag 8 when it is deflated. An air compressor 12 supplies air through tubes 14 and 16 to the pneumatically inflatable bag 8. An air valve 18 is controlled by a switch 20 located conveniently below the work supporting plate 2 at knee level for controlling the air pressure to the bag 8. When the knee is not depressing switch 20, the bag 8 becomes deflated. A back up plate 22 in combination with clamps 24 secured to the work supporting plate 2 prevent the pneumatically inflatable bag 8 from moving away from the

grinder wheel when the bag 8 is inflated against the casting advancing it to the grinding surface 6. The back up plate 22 is perpendicular to the work supporting plate 2. The pneumatically inflatable bag 8 is secured to the back up plate 22 by bolts 23 through lugs 26. The distance between the back up plate 22 and the grinder wheel 4 can be varied by unthreading the screws 28 which hold the clamps 24 securing the back up plate 22 and repositioning the back up plate 22 to allow for varying sizes of castings.

10 In operation a casting 30 having a riser is urged against the grinding wheel surface 6 by an operator opening the air valve 18 by depressing the switch 20 with his knee. The pneumatically inflatable bag 8 urges and advances the work 30 (casting) against the grinder wheel surface 6. To remove or to 15 reposition the casting 30 against the grinding wheel surface 6, the operator releases the knee switch 20 and the air is allowed to escape from the pneumatically inflatable bag 8 whereby the bag 8 is collapsed and the casting 30 can be repositioned freely. Another advantage in using the inflatable bag 8 is that it 20 can apply a uniform pressure against a casting having an irregular contour. This uniform pressure cannot be accomplished by using a rigid member for advancing the work against the grinder wheel surface 6.

I claim:

25 1. An apparatus for feeding work to a grinder wheel which comprises:

- a. a grinder wheel;
- b. a work supporting plate positioned adjacent to the grinder wheel and perpendicular to a grinding surface of the wheel;
- c. a pneumatically inflatable bag positioned on the work supporting plate and spaced from an edge of the work supporting plate nearest the grinder wheel;
- d. means supplying air to inflate the bag; and
- e. means preventing the bag from moving away from the grinder wheel when the bag urges the work to the grinder wheel.

2. An apparatus as recited in claim 1 wherein the means preventing the bag from moving away from the grinder wheel includes a plate perpendicular to the supporting plate.

3. An apparatus as recited in claim 1 wherein the means supplying air includes a control valve switch located below the work supporting plate.

4. An apparatus as recited in claim 2 wherein the means preventing the bag from moving away from the grinder includes means adjustably securing the plate on the supporting plate.

5. An apparatus for feeding work to a grinder wheel which comprises:

- a. a grinder wheel;
- b. a work supporting plate positioned adjacent to the grinder wheel and perpendicular to a grinding surface of the wheel;
- c. an inflatable bag positioned on the work supporting plate and spaced from an edge of the work supporting plate nearest the grinder wheel;
- d. means supplying inflating material to inflate the bag; and
- e. means preventing the bag from moving away from the grinder wheel when the bag urges the work to the grinder wheel.

UNITED STATES PATENT OFFICE
CERTIFICATE OF CORRECTION

Patent No. 3,648,415 Dated March 14, 1972

Inventor(s) James G. Bair

It is certified that error appears in the above-identified patent and that said Letters Patent are hereby corrected as shown below:

Column 1, line 20, after "work", first occurrence, cancel "to the work". Column 2, line 8, "the clamps" should read -- plate --.

Signed and sealed this 24th day of October 1972.
